UNITED STATES

UNITED STATES PATENT OFFICE

2,159,716

Victor J. Sigoda, Brooklyn, N. Y., assignor to
Man-Sew Pinking Attachment Corp., New
York, N. Y., a corporation of New York

Application October 2, 1937, Serial No. 166,925

20 Claims (Cl. 164-175)

My present invention relates to machines for pinking or trimming goods, work in process of manufacture into garments, garments, and in general materials the edges of which are to be safeguarded against unraveling.

An object of the invention is to provide a compact, simplified self-contained pinking machine, one comprising a complete unit in itself, ready to be mounted upon a work table or bench and to be connected up with a source of power for its operation.

Another object of the invention is to provide a construction in which the operator will not be hampered by superstructure but will have ample space in which to manipulate the work to best advantage.

A further object of the invention is the provision of a pinking machine having a yielding work feed and a cooperatively yielding drive for the feed, these parts being constructed and arranged to yieldingly press against one another for seizing and feeding work of all kinds in an efficient manner.

Still a further object of the invention is the provision of an organization having its parts so constructed and arranged that I may employ a bottom pinking cutter in the form of a disc which may be horizontally disposed in the cloth-plate for rotation, and in this connection to make the feed mechanism in the form of a pressure roller constructed to engage both the driving means and the pinking cutter and whose pressural force is exerted downwardly not only upon the driving means therefor but also upon the teeth of the cutter whereby to pink the work which is being fed.

Other objects will appear hereinafter.

The invention consists in the construction, combination and relative arrangements of parts as will be described more fully in the following specification and illustrated in the accompanying drawing, forming a material part of this specification and in which:

Fig. 1 is a vertical sectional view of a pinking machine made in accordance with the invention.

Fig. 2 is a partial top plan and section taken on the line 2—2 of Fig. 1; and

Fig. 3 is a vertical end view and section taken on the line 3—3 of Fig. 1.

Referring to the accompanying drawing in which for purposes of illustration only, I have shown a preferred embodiment of my invention, 10 denotes a cloth-plate which may be mounted upon a work bench, a work table or any other

appropriate support. The cloth-plate supports all parts of the machine.

Rising from the right-hand end of the cloth-plate is a vertical housing 1 in which are vertical and horizontal shafts 12 and 13, respectively, the shaft 12 being mounted in bearings 14 and 15, and the shaft 13 in bearings 16 and 17. Said shaft 13 for its operation, has a pulley 18 which is connected by a belt (not shown) to any suitable source of power. Through the intermeshing gear-
ing 19 and 20, the shaft 12 is driven from the shaft 13.

Secured upon the cloth-plate by bolts or equivalent means is a casting body 21 having a long integral arm 22, which, it will be observed, is spaced a distance above the cloth-plate so that there will be ample room for work of various kinds to be manipulated by the operator upon the cloth-plate below said arm. 23 is a pressure jaw which is disposed upon the arm 22, its outer end portion 24 extending downwardly along the outer end of the arm and being suitably bifurcated at 25 in order to carry the rotatable pressure roller 26. The jaw 23 is mounted for vertical adjusting or yielding movement. It is provided with a pivot screw 27 the plain or non-threaded lower end 28 of which fits in a socket in the arm 22 whereby through the manipulation of the nut 29 the screw may be made to support the jaw in spaced relation to the top surface of the arm. 30

The jaw 23 may move up and down on adjusting pin 30 the lower end 31 of which is threaded into the arm 22. A finger operated wing-nut 32 is threaded upon the upper portion of the pin and through its manipulation the tensional force of a coiled spring 33 may be increased or decreased, said spring being coiled around the pin and imprisoned between the wing-nut and its seat 34 in the jaw. 35

40
its seat 34 in the jaw.
Rotatably located below the arm in the cloth-
plate is the bottom pinking cutter in the form
of a disc-shaped member 35 having upwardly-
presented teeth 36 adjacent its periphery. In
the present embodiment, the cutter is represented
as secured through a screw 37 to a short vertical 45
shaft 38 rotatable in a bearing 39 fixed to the
cloth-plate. Said shaft 38 receives its rotary
movement through the gears 40 and 41 from
underneath shaft 42 which, in turn is operated
through the gears 43 and 44 from vertical shaft 50
12. Suitable bearings 45, 46 and 47, fixed to the
cloth-plate, support the shaft 42.
48 is a stationary shaft which is secured, in the
present instance, to bearing 47 and supported
thereby. Rotatably surrounding this shaft is a
cutter 51.

sleeve 49 one end of which is fixed to gear 50 which is in mesh with gear 51 whereby to be operated from the shaft 42.

For yieldingly cooperating with and frictionally driving the pressure roller 26, I provide a disc 52 having a large central opening surrounding the sleeve 49 and which is frictionally held between two disc shaped plates 53 and 54. A stout coiled spring 55 surrounds the shaft 48 with its outer end abutting a collar 56 so as to force the arrangement of discs tightly against one another with the disc 53 tightly pressing against the gear 50. It is to be observed that the parts are so arranged that the driving disc 52 is frictionally maintained between the discs 53 and 54 and in such position that its milled periphery 57 will be in frictional driving and feeding contact with the surface of the pressure roller 26. In operation, the friction disc due to the pressure thereon of the roller 26 and of any work passing between these two parts is in an eccentric position but tends always to assume a concentric position.

From an inspection of Fig. 2, it will be noted that the driving disc and pinking cutter are arranged to operate in relatively close relation and in Fig. 1 it will be seen that the face of the pressure roller is relatively wide so that at the same time it engages the periphery of the disc and the upwardly-facing teeth of the cutter. Shaft 42 serves as means through which to transmit power for the cutter and for the roller, the latter under the arrangement being positively driven. The work, seized between the pressure roller above it and the driving disc and cutter below it, is smoothly fed and simultaneously pinked. Through the adjustment of wing-nut 32 the downward yielding pressure of the roller may be regulated in accordance with the conditions of work which are encountered. With my improved pinking machine, thin, delicate fabrics, relatively heavy fabrics and layers of fabrics may be pinked with equal facility, and it will be understood that the pinking operation takes place continuously with the feeding of the work.

While I have illustrated and described the preferred form of construction for carrying my invention into effect, this is capable of variation and modification without departing from the spirit of the invention. I, therefore, do not wish to be limited to the details of construction set forth but desire to avail myself of such variations and modifications as come within the scope of the appended claims.

I claim:

1. A pinking machine comprising in combination with a support, pinking means, feeding means for the work including a pressure roller cooperating with the pinking means to pink the work and a member for driving said roller, both the roller and said driving member being yieldable.

2. A pinking machine comprising a pinking cutter and means for rotating it, feeding means for the work including a pressure roller and a friction drive member, said roller being arranged for engagement with the drive member and for exerting pressure upon the cutter whereby to pink the work.

3. In a pinking machine, the combination of a pressure roller, a pinking cutter engaged by the roller, a friction drive member engaging the roller, and means for simultaneously operating the cutter and drive member.

4. In a pinking machine, a pinking cutter, a friction driving disc, means for operating the

cutter and driving disc simultaneously, a pressure element in cooperation with the teeth of said cutter whereby to pink work and engaged with said driving disc whereby to be driven, said element being yieldably mounted for movement 5 toward and away from said parts.

5. In a pinking machine, a pinking cutter, a friction driving disc, means for operating the cutter and disc simultaneously, a pressure roller for exerting pressure on the teeth of said cutter 10 and on the periphery of said disc, said roller and disc being mounted for relative yielding movement.

6. A pinking machine having a drive shaft, a cloth-plate supporting the same, a rotary pinking cutter and means for operating the same from the drive shaft, a rotary friction disc and means for operating the same from the drive shaft, and a pressure roller mounted for relatively yielding movement, said roller having a relatively wide 20 face portion for engaging the friction disc to seize and feed work therewith and for engaging the cutter to seize and pink work therewith.

7. In a pinking machine, a pinking cutter, a friction driving disc, means for operating the 25 cutter and driving disc, a pressure element in cooperation with the disc to seize and feed work therewith and also with the cutter to seize and pink the work, said driving disc being mounted for eccentric movement, and means associated 30 with said disc for yieldingly resisting the eccentric movement thereof.

8. A pinking machine having feed mechanism comprising a driving member and a driven member, peripherally bearing on one another to seize 35 and feed work, one of said members being mounted for eccentric movement and having means associated therewith yieldingly resisting the eccentric movement thereof.

9. In a pinking machine, the combination of a 40 rotary pinking cutter, a friction driving disc, means mounting the disc for eccentric yielding movement, a pressure roller having a face portion for engaging the periphery of the disc and the teeth of the pinking cutter, said roller being 45 mounted for yielding movement and manually operated means for regulating the pressure of the roller upon the disc and teeth of the pinking cutter.

10. A pinking machine having a cloth-plate, a support thereon with an arm extending above the cloth-plate, a jaw mounted for adjustment on the arm and having a portion carrying a pressure roller adjacent the cloth-plate, a pinking cutter disposed for rotation in the cloth-plate 55 and having pinking teeth, a driving disc disposed to rotate through an opening in the cloth-plate adjacent the teeth of the pinking cutter, said roller having a face portion for simultaneously engaging the teeth of the cutter and the periphery of the disc.

11. A pinking machine having a cloth-plate and a pinking cutter, a support on the cloth-plate having an overhanging arm, means mounted on the arm carrying a roller engaging the teeth 65 of the cutter, and a driving disc disposed for operation with its periphery engaging the roller, said disc and roller cooperating to seize and feed work and said roller and cutter cooperating to pink the work.

12. In a pinking machine, means for seizing and feeding work including a friction drive member, means for pinking the work as it is fed, means for driving the pinking means, means for mounting the friction drive member for eccentric 75

tric movement, including a stationary shaft and spring pressed parts thereon frictionally engaging the drive member, and means for driving one of said parts.

5 13. In a pinking machine, a vertical shaft supporting a pinking cutter, a pressure element for operating on the cutter, a horizontal stationary shaft, rotatable means thereon frictionally carrying an eccentrically movable disc cooperating with the pressure element to seize and feed work operated on by the cutter, a main shaft, means for operating the vertical shaft from the main shaft, and means driven by the main shaft for operating the rotatable means carrying said disc.

10 14. In a pinking machine, a rotatably mounted pinking cutter, a work feeding member mounted to rotate in a plane tangent to the cutter and substantially parallel with the axis thereof, and means common to said cutter and feeding member for yieldingly pressing the work thereon.

15 15. In a pinking machine, a rotatably mounted pinking cutter, a feeding member mounted to rotate in a plane substantially parallel with the cutter axis and for bodily movement in said plane, operating means for said cutter and feeding member, and means cooperating with said feeding member to seize and feed the work to said cutter.

20 16. In a pinking machine, a pressure member to engage one side of the work, a cooperating feeding member to engage the opposite side of the work, a shaft for operating said feeding

member, and means operatively connecting said feeding member with said shaft and permitting bodily displacement of said member relative to the pressure member.

25 17. In a pinking machine, a pressure member to engage one side of the work, a cooperating feeding member to engage the opposite side of the work, a shaft for rotating said feeding member, and a frictional driving connection between said member and shaft, permitting eccentric displacement of the feeding member relative to the shaft axis.

18. In a pinking machine, a pinking cutter mounted to rotate in a horizontal plane, a work feeding member mounted to rotate in a vertical plane, and means for pressing the work directly into contact with said feeding member and cutter.

15 19. In a pinking machine, a pinking cutter mounted to rotate in a horizontal plane, a work feeding member mounted to rotate in a vertical plane, means for pressing the work simultaneously into contact with said feeding member and cutter, and means permitting relative bodily movement between the feeding member and pressing means in angular relation to the cutter.

20 20. In a pinking machine, a rotatably mounted pinking cutter, a member movable relative to the cutter for feeding work to the latter, and means common to said cutter and feeding member and directly engaging the work to press the same thereon.

25 VICTOR J. SIGODA.
